UNITED STATES PATENT OFFICE.

JOHN F. HEMENWAY, OF NEW YORK, N. Y.

PRESSURE-RELEASE FOR CLOTHES-WRINGERS.

1,220,119.

Specification of Letters Patent. Patented Mar. 20, 1917.

Application filed October 2, 1916. Serial No. 123,378.

To all whom it may concern:

Be it known that I, JOHN F. HEMENWAY, a citizen of the United States, residing at New York city, in the county of New York and State of New York, have invented certain new and useful Improvements in Pressure-Release for Clothes-Wringers, of which the following is a specification, reference being had therein to the accompanying drawing.

This invention relates to certain new and useful improvements in pressure release for clothes wringers, the object being to provide a release which is so constructed that the releasing member will form a stop for the movably mounted top bar of the clothes wringer when moved in position to release the pressure on the pressure rolls so as to prevent the top bar from becoming detached from the wringer frame.

Another object of my invention is to provide a pressure release in which a pair of releasing bars are carried by the top bar and coöperate with pivoted latches carried thereby which are normally arranged in keepers carried by the frame of the wringer so that when said latches are moved in position to release the pressure on the pressure rolls, the tail of the latch will be thrown into position to coöperate with the keeper for preventing the top bar from becoming detached from the wringer frame.

Other and further objects and advantages of the invention will be hereinafter set forth and the novel features thereof defined by the appended claims.

In the drawings,

Figure 1 is a detail side elevation of a portion of the clothes wringer partly in section showing the application of my improved construction of pressure release thereto; and

Fig. 2 is a perspective view of a release detached.

Like numerals of reference refer to like parts in the several figures of the drawing.

In the drawing I have shown a portion of a clothes wringer of the ordinary construction now in use in which a frame 1 is employed having pressure rolls slidably mounted therein, not shown, above which is arranged pressure means 2 which is engaged by pressure screws 3 carried by a movably mounted top bar 4 mounted within the wringer frame. The pressure screws 3 are mounted in threaded boxes 5 carried by

the top bar 4, said boxes being provided with extensions 6 having slots 7 formed therein to provide a pivot 8 over which is adapted to be placed a lip 9 of a pivoted latch 10, 60 said lip being compressed around the pivot 8 so as to securely fasten the pivoted latch 10 to the extension of the threaded boxes as clearly shown.

The end of the top bar 4 is cut away as 65 shown at 11 to provide a recess in which the upper portion of the pivoted latch 10 is adapted to work, said latch having a lateral extension 12 which is adapted to engage the upper wall 13 of a slotted plate 14 70 secured to the side bars of the wringer frame, but it is, of course, understood that one of these plates is carried by the upper end of each of the side bars and that each end of the movably mounted top bar is provided 75 with a pivoted latch. The pivoted latch is provided at its lower end with an extension 15 forming a weight for holding the latch in the position as shown in Fig. 1. The upper and lower lateral extensions of the 80 latch 10 are normally held within the slot of the plate 14, the upper extension engaging the upper end of the slot so as to hold the top bar in predetermined position within the wringer frame. 85

In order to provide means for swinging the latches 10 on their pivots, I provide the top bar with guideways 16 in which are slidably mounted releasing bars 17 having beveled inner ends 18 adapted to be engaged 90 by the conical shaped lower end 19 of the shank 20 of a push button 21 which is slidably mounted in the top bar as clearly shown, and is surrounded by a spring 22 for normally holding the same in extended position, the lower end of said shank being preferably provided with a head 23 for preventing the push button from becoming detached from the top bar. The outer ends of the releasing bars 17 are offset as shown, 100 and are provided with slots 24 through which the pressure screws 3 pass so as to allow the releasing bars to move laterally when the same is forced apart by the wedging action of the push button. The extreme ends of the releasing bars are reduced as shown at 24, and are adapted to engage the pivoted latches 10 below their pivots so as to spring the upper extensions 12 out of the slots of the plates 14 in order 105 to allow the movably mounted top bar to move vertically within the wringer frame 110

to release the pressure on the pressure rolls. As the upper extensions are moved out of the slots of the plates 14, the weighted lower ends of the pivoted latches are moved into 5 the slot so that as the top bar moves vertically by the expansion of the pressure means, the lateral extensions 15 engage the upper walls of the slot and prevent the top bar from becoming detached from the frame.

10 From the foregoing description, it will be seen that I have provided a pressure roll release for a clothes wringer in which the pivoted latch employed for holding the top bar in predetermined position within the 15 frame, forms a stop for the movably mounted top bar in order to prevent the top bar from jumping out of the wringer frame when the pressure is released.

I claim:

20 1. A clothes wringer, comprising a frame having pressure rolls and pressure means for said rolls mounted therein, a movably mounted top bar having means for adjusting said pressure means, pivoted latches carried by said top bar for holding said top bar in adjusted position within said frame, and releasing bars engaging said latches for releasing said top bar, said latches having tail portions for limiting the upward movement of said top bar.

2. A clothes wringer comprising a frame having pressure rolls and pressure means for said rolls mounted therein, a top bar having means for adjusting said pressure means, keepers carried by said frame, pivoted latches carried by the top bar engaging said keepers for holding said top bar in predetermined position within said frame, means carried by the top bar for actuating 35 said latches for releasing said top bar, and means carried by said latches for limiting the upward movement of the top bar in said frame.

3. A clothes wringer, comprising a frame 45 having pressure rolls and pressure means for said rolls mounted therein, a top bar having means for adjusting said pressure means, keepers carried by the side bars of said frame, pivoted latches carried by the 50 top bar cooperating with said keepers, releasing bars carried by the top bar, and means mounted in the top bar engaging said releasing bars for moving said latches in position to release said top bar, said 55 latches having tail portions cooperating with said keepers for limiting the upward movement of the top bar within said frame.

4. A clothes wringer comprising a frame having pressure rolls and pressure means 60 for said rolls mounted therein, a top bar movably mounted in said frame having pressure screws for adjusting said pressure means, plates carried by the side bars provided with slots, latches pivotally mounted 65 in the ends of the said top bar extending

into said slots for normally holding said top bar in predetermined position within said frame, and releasing means carried by the top bar engaging said latches for moving said latches in position to allow said top bar to move a predetermined distance within said frame.

5. A clothes wringer comprising a frame having pressure rolls and pressure means for said rolls mounted therein, a top bar 75 movably mounted in said frame having means for adjusting said pressure means, slotted plates carried by the side bars of said frame, pivoted latches carried by the top bar having laterally projecting portions 80 extending into the slots of said plates, releasing bar slidably mounted on said top bar, means carried by said top bar engaging said releasing bar for forcing said releasing bar into engagement with said 85 latches for moving the extensions of said latches out of the slots of said plates for releasing said top bar, and members carried by said latches coöperating with the slots of said plates for limiting the upward 90 movement of said top bar within said frame.

6. A clothes wringer, comprising a frame having pressure rolls and pressure means for said rolls mounted therein, a top bar 95 movably mounted in said frame having pressure screws for adjusting said pressure means, slotted plates carried by the side bars of said frame, pivoted latches carried by the top bar having laterally disposed 100 spaced portions extending into the slots of said plates for normally holding said top bar in predetermined position within said frame, and releasing means carried by the top bar engaging said latches for moving 105 one of said extensions out of the slot of said plate for allowing said top bar to move a predetermined distance within said frame to release said pressure means.

7. A clothes wringer, comprising a frame 110 having pressure rolls and pressure means for said rolls mounted therein, a top bar movably mounted in said frame having boxes carrying pressure screws for adjusting said pressure means, plates carried by the side bars of said frame provided with slots, latches pivotally carried by the boxes of said top bar having laterally projecting spaced portions extending into the slots of said plates for normally holding said top 115 bar in predetermined position within said frame, and means carried by the top bar engaging said latches for moving one of said extensions out of contact with said plates for allowing said top bar to move 120 a predetermined distance within said frame.

8. A clothes wringer comprising a frame having pressure rolls and pressure means for said rolls mounted therein, a top bar 125 movably mounted in said frame having

- means for adjusting said pressure means, said top bar having recesses at its ends, pivoted latches mounted in the recesses of said top bar having spaced members extending therefrom, slotted plates carried by the side bars of said frame adapted to receive the spaced members of said latches, and means carried by the top bar engaging said latches for moving one of said spaced members of each latch out of the slot of the adjacent plate to allow said top bar to move upwardly a predetermined distance within said frame.
9. A clothes wringer, comprising a frame having pressure rolls and pressure means for said rolls mounted therein, a top bar movably mounted in said frame, threaded boxes carried by said top bar, pressure screws mounted in said boxes for adjusting said pressure means, said boxes having extensions provided with pivots, latches mounted on said pivots having spaced laterally projecting portions, plates carried by the side bars of said frame having slots to receive said laterally projecting portions of said latches, and means carried by the top bar engaging said latches for moving one of the extensions of each pivoted latch out of the slot of said plates for allowing said top bar to move a predetermined distance within said frame.
10. A clothes wringer, comprising a frame having pressure rolls and pressure means for said rolls mounted therein, a top bar movably mounted in said frame having pressure screws for adjusting said pressure means, plates carried by the side bars of said frame provided with slots, pivoted latches carried by the ends of the top bar having laterally projecting portions extending into the slots of said plates, the upper extension of each latch engaging the upper end of each slot for normally holding said top bar in predetermined position within said frame, and means carried by the top bar for moving the upper extension of each latch out of the slot of said plate to release said top bar and the lower extension of each latch in position to engage the upper wall of said slot for limiting the upward movement of said top bar within said frame.
11. A clothes wringer comprising a frame having pressure rolls and pressure means for said rolls mounted therein, a movably mounted top bar, carrying means for adjusting said pressure means, keepers carried by the side bars, pivoted latches carried by the movably mounted top bar having portions engaging said keepers for holding said top bar in adjusted position within said frame, releasing bars carried by said top bar, and a push button slidably mounted in said top bar coöperating with said releasing bars for moving said releasing bars in position to swing the portions of the said latches out of said keepers, and means carried by the latches coöperating with said keepers for limiting the upward movement of said top bar.
- In testimony whereof I hereunto affix my signature in the presence of two witnesses.
